SKI BINDING

Howard Jansen, Chicago, Ill.

Application June 10, 1947, Serial No. 753,709

2 Claims. (Cl. 280—11.35)

1

This invention relates to ski bindings and has as its general object to provide a novel and improved ski binding of sturdy construction which is convenient to manipulate and adjust and inexpensive to manufacture.

Other objects are to provide a simplified form of binding having relatively few parts to obviate the necessity for the more intricate and expensive flexible cable which is ordinarily employed as a heel clamp, and to provide a universal ski binding which may be used with any size or type of boot without making any permanent or semi-permanent adjustments in clamping plates and other parts of the binding, and without requiring the attachment of plates or other complementary parts to the boots. Another object is to provide a binding to fit any size boot by manipulation of a single length adjustment and clamping lever when the ski is put on. Another object is to provide a binding having improved automatic release action in a fall. Still another object is to provide a novel heel clamp.

These and other objects will become apparent as the description proceeds in connection with the accompanying drawings illustrating a preferred embodiment of the invention. This application is a continuation-in-part of my copending application, Serial No. 696,753, filed September 13, 1946, for Adjustable Cable Fastener for Ski Binding. The said copending application is now Patent No. 2,567,772, issued September 11, 1951.

In the drawings:

Figure 1 is a plan view of a ski illustrating the present binding;

Figure 2 is a side elevation view of the parts shown in Figure 1 with a boot shown in phantom;

Figure 3 is an enlarged fragmentary elevation view showing the clamping lever in released position; and

Figure 4 is a cross sectional view taken on the line 4—4 of Figure 1.

The ski 10 has affixed thereto a toe clamping or stop plate 11 secured to the ski by a plurality of screws 12. The numeral 13 designates a sole plate which may be an integral part of the toe clamping plate 11 or which may be a separate plate secured under the heads of the screws 12 on top of the plate 11. Regardless of whether the parts 11 and 13 are separate or integral they are permanently and non-adjustably secured to the ski by these screws. The forward end of the plate 11 is provided with a boot engaging lip 14 which is curved in plan view as shown in Fig-

2

ure 1 to center the toe of the boot on the ski so that it cannot swing from side to side, and which is curved or cupped back sufficiently to engage the end of the sole of the boot 15 shown in Figure 2 so that the toe of the boot will not normally lift away from the ski.

The plate 11 has a flat base portion comprising a pair of spaced parallel strips 16 on opposite sides of the ski to receive the screws 12. The strips 16 form longitudinal guides for a tongue 20 which is thereby enclosed between the top surface of the ski and the plate 13 with sufficient clearance to provide a sliding fit. Preferably the tongue 20 contacts the strips 16 only at the tips 17 of a pair of oppositely disposed projections 17 on the strips near their rear ends. For the rest of their length, forwardly from projections 17, the strips 16 are recessed away from contact with the tongue 20 as indicated at 18 to avoid a long slip fit which might jam from rust or dirt, and for another reason which will presently appear.

The rear end of the tongue 20 is provided with an upstanding lip 21 which is curved both in plan and in elevation as shown to engage and center the heel of the boot. The lip 21 may be designed to engage the heel on other boots as well as the usual cable groove in the heel on a ski boot, and since the toe lip 14 is equally capable of engaging and centering the sole of an ordinary walking boot the present binding is not necessarily limited to use with specially designed ski boots, as are most conventional bindings. There are no lateral clamps and no parts to be attached to the boots. A tension spring 22 anchored to the ski by the screw 23 tends to extend the tongue 20 rearwardly to receive the boot when the clamping mechanism presently to be described is released. This spring also tends to hold the ski up against the heel of the boot when the foot is raised. The numeral 19 designates a flexible wire or chain connected between the screw 23 and the tongue to prevent stretching of the spring beyond its elastic limit.

The forward end of the tongue 20 has a longitudinal slot 24 to receive a screw 25 to hold the tongue down where it extends in front of the plate 11 and to provide lateral guidance for the sliding tongue. This screw is located to align the tongue for the proper lateral positioning of the heel of the boot on the ski since the recesses 18 allow for considerable lateral adjustment of the tongue between the strips 16. Thus the screw 25 may be moved to one side or the other to swing the tongue around one of the projections 17 as a center, it being understood that the screw is left

loose enough to allow the tongue to slide freely. After this screw is secured in place the tongue 20 is restrained from twisting on the ski to thereby hold the ski in proper alignment with the boot. The tongue is sufficiently flexible in a vertical direction to permit the heel to rise up off the ski in walking.

The tongue is pulled forwardly into clamping position by one or more springs 26 of sufficient tension attached to a bail 27 which is pivotally connected at 28 with an overcenter clamping lever 30. The clamping lever 30 has two parallel side walls 31 in which a transverse fulcrum pin 32 is secured. This fulcrum pin is receivable in any one of a series of notches 33 in the upper edges of the upstanding parallel sides of a base plate 34 which is attached to the ski by screws 35 and 36. A resilient guard 37 is also secured under the heads of these screws to hold the fulcrum pin 32 in the notch in which it is placed, while at the same time permitting the pin to be moved from notch to notch to change the length adjustment of the binding. If desired, one of the screws such as the screw 35 may be left somewhat loose to allow the guard 37 to spring more readily in moving the fulcrum pin from one notch to another.

The present construction provides a binding which is adaptable by a single convenient adjustment to shoes or boots of any size, length or style. The width of the boot is immaterial because there are no side clamping plates. Regardless of its width or shape the boot is automatically centered on the ski by the curvature of the clamping lips 14 and 21 as shown in plan view in Figure 1. When the free end of the clamping lever 30 is snapped down against the ski, the bail 27 passes over center with respect to the fulcrum pin 32 to hold the binding in clamped condition. The rear spring 22 exerts considerably less tension than the spring 26, whereby substantially the full tension applied by the clamp is effective on the tongue 20 to clamp the heel of the boot and to hold the toe of the boot securely in the lip 14. The toe of the boot is held down firmly against the ski at all times, but the heel is free to rise to a limited extent against the resilient restraint of the tongue 20 in bending and the spring 22 in stretching. Thus, the ski is held firmly to the boot for purposes of skiing but in the event of a fall, both the heel and toe of the boot are readily releasable by a strong twisting or sidewise movement.

A further important advantage of the present binding is its release in a forward fall. The length of the chain 19 allows the heel to rise off the ski sufficiently for normal use without becoming taut, but in a forward fall the chain pulls the lip 21 out of engagement with the boot heel to thereby completely release the binding from the boot. The toe of the boot is also releasable by an abnormal upward pull.

Various changes may be made in the construction and arrangement of parts and all such modifications within the scope of the appended claims are included in the invention.

Having now described my invention and in what manner the same may be used, what I claim as new and desire to protect by Letters Patent is:

1. In a ski binding for securing a boot to a ski, a toe stop plate having a flat base portion to extend under the shoe sole and be secured to the top surface of the ski, a transverse upstanding lip on the forward edge of said base portion to hold the toe of the boot for skiing and to release the boot in case of an abnormal upward or lateral pull, a flexible tongue slidable through said stop plate to engage the heel of the boot, guide means for said tongue in said stop plate allowing said tongue to slide longitudinally and swing laterally, a slot in the forward end of said tongue, and guide means in said slot adapted to be secured to the ski in adjusted position in front of said stop plate to adjust the lateral position of the heel engaging portion of the tongue prior to use of the binding.

2. In a ski binding for a boot, a toe stop plate having a flat base portion to be secured rigidly to the top surface of a ski without projecting over or beyond the side edges of the ski, a transverse upstanding lip on the forward edge of said base portion arranged so that said base portion extends back under the sole of a boot in skiing position on the ski, said lip being curved rearwardly at its upper edge at an angle to the horizontal sufficient to hold the toe of the boot on the ski in normal skiing without impeding upward release of the toe of the boot in an abnormal upward pull and said lip being curved laterally sufficiently to hold the toe of the boot centered on the ski without impeding sidewise release in an abnormal twist or lateral pull on the boot, a pair of guides in said base portion, and a longitudinal slidable flat heel engaging tongue in said guides, said guides having opposed rounded projections under said base portion to engage and guide said tongue with the ends of the tongue in different lateral positions of adjustment, said upstanding lip and said heel engaging tongue constituting the sole means for securing the boot to the ski.

HOWARD JANSEN.
